UNITED STATES PATENT OFFICE

126,791

DESIGN FOR A SACNET TASSEL DOLL

Benjamin Levitt, Newark, and Leo Aronson,
Hillside, N. J., assignors to A. L. Siegel Co., Inc.,
Newark, N. J., a corporation of New York

Application January 8, 1941, Serial No. 97,891

Term of patent 7 years

To all whom it may concern:

Be it known that we, Benjamin Levitt and Leo Aronson, citizens of the United States and residents, respectively, of Newark, county of Essex, and State of New Jersey, and Hillside, county of Union, and State of New Jersey, have invented a new, original, and ornamental Design for a Sachet Tassel Doll, of which the following is a specification, reference being had to the accompanying drawing forming a part thereof, wherein:

We claim:

The ornamental design for a sachet tassel doll, as shown.

BENJAMIN LEVITT.
LEO ARONSON.
